No. 13,366

Oct 24, 1882

UNITED STATES PATENT OFFICE.

EDWARD B. TOWLE, OF NEWBURYPORT, MASSACHUSETTS, ASSIGNOR TO THE TOWLE MANUFACTURING COMPANY, OF SAME PLACE.

DESIGN FOR A HANDLE FOR A KNIFE, FORK, OR SPOON.

SPECIFICATION forming part of Design No. 13,366, dated October 24, 1882.

Application filed July 11, 1882. Term of patent 7 years.

To all whom it may concern:

Be it known that I, EDWARD B. TOWLE, of Newburyport, in the county of Essex and State of Massachusetts, have originated and 5 designed a new and original Impression, Ornament, or Pattern for the Handles of Knives, Forks, or Spoons, of which the following is a full, clear, and exact description, reference being had to the annexed photographs, which 10 are made a part of this specification.

The impression, ornament, or pattern, the configuration of which is shown by the annexed photographs, consists of two portions, the more elaborate of which is intended for 15 the front or upper side of the handle and the less elaborate portion for the back or lower side, and each portion is stamped, engraved, or otherwise placed or worked upon the proper side of the handle.

What I claim as my invention, and desire to 20 secure by Letters Patent, is—

The impression, ornament, or pattern herein described, and represented by the annexed photographs, whether stamped, engraved, or otherwise placed upon or worked into the handles of knives, forks, and spoons. 25

EDWARD B. TOWLE.
